220,150

PORTABLE BARBECUE STOVE

Joe E. Roestenburg, Trinidad, Colo., assignor to William J. Tracy, as trustee for S. Double R Trust, 1st National Bank of Trinidad, Colo.

Filed Oct. 6, 1969, Ser. No. 19,438

Term of patent 14 years

Int. Cl. D7—04

U.S. Cl. D81—10

779-2

FIG. 1 is a perspective view of a portable barbecue stove showing my new design; and,

FIG. 2 is a side elevational view thereof.

The sides of the stove not shown are similar to the sides shown.

I claim:

The ornamental design for a portable barbecue stove, as shown and described.

References Cited
UNITED STATES PATENTS

D. 131,008	1/1942	Howard	-----	D81—10
1,298,762	4/1919	Milligan.
3,109,420	11/1963	Ott et al.	-----	126—9
3,447,530	6/1969	Santeramo	-----	126—25

FOREIGN PATENTS

262,857 12/1926 Great Britain.

OTHER REFERENCES

House Beautiful, April 1953, page 78, midget charcoal grill.

J. PAUL GUERTIN, Primary Examiner